(57) **CLAIM**

The ornamental design for a tamper-evident securing device, as shown and described.

DESCRIPTION

FIG. 1 is a perspective illustration of an embodiment of the tamper-evident securing device according to our design, the perspective being from the top rear end of the securing device; FIG. 2 is a perspective illustration thereof, the perspective being from the bottom front end of the securing device;

FIG. 3 is a left side view thereof, the right side view being a mirror image thereof;

FIG. 4 is a bottom plan view thereof;

FIG. 5 is a top plan view thereof;

FIG. 6 is a front end view thereof;

FIG. 7 is a rear end view thereof; and,

FIG. 8 is a perspective illustration thereof showing an environment of use of the tamper-evident securing device, the perspective being from the bottom front end of the securing device.

The broken lines depict unclaimed environmental subject matter.
